US0D1092778S

(12) **United States Design Patent** (10) **Patent No.:** **US D1,092,778 S**
(45) **Date of Patent:** **** Sep. 9, 2025**

(54) **DETECTION CUP**

(71) Applicant: **Hangzhou Laihe Biotech Co., Ltd.,**
Zhejiang (CN)

(72) Inventor: **Weiwei Ye**, Zhejiang (CN)

(73) Assignee: **HANGZHOU LAIHE BIOTECH CO., LTD.**, Zhejiang (CN)

(**) Term: **15 Years**

(21) Appl. No.: **29/940,588**

(22) Filed: **May 3, 2024**

(30) **Foreign Application Priority Data**

Apr. 7, 2024 (CN) 202430186404.9
